UNITED STATES PATENT OFFICE

LOUIS ARTHUR ROBITAILLE, OF MONTREAL, QUEBEC, CANADA

SHEET-METAL-RADIATOR-FORMING MACHINE

Application filed January 28, 1929, Serial No. 335,802, and in Canada June 9, 1928.

The invention relates to a sheet metal radiator forming machine, as described in the present specification and illustrated in the accompanying drawings that form part of the same.

The invention consists essentially of the novel features of construction pointed out broadly and specifically in the claims for novelty following a description containing an explanation in detail of an acceptable form of the invention.

The objects of the invention are to construct a sheet metal radiator at the least possible expenditure of money and at the same time facilitate and insure efficiency in the manufacture of this particular type of radiator; to maintain the equality in the curls of a radiator, in which a tortuous and continuous path without obstructions is made for the course of the fluid; to bring these radiators in so far as the public are concerned, within the reach of all, and thereby enable those of an economical turn of mind to enjoy all the advantages of the sheet metal radiator at a comparatively low cost; and generally to provide an efficient machine adapted for the purpose of producing sheet metal radiators of a durable nature with uninterrupted fluid passages.

In the drawings, Figure 1 is a side elevational view of the machine showing a sheet of metal partially formed by means of the rollers.

Figure 2 is an end elevational view of the machine.

Figure 3 is a plan view showing a few of the upper rollers and their spacing members and the upper end blocks.

Figure 4 is a longitudinal sectional view of the machine on the line 4—4 in Figure 2.

Figure 5 is a vertical sectional view of the machine on the line 5—5 in Figure 1.

Figure 6 is a diagrammatic view showing the movement of the first roller to the block.

Figure 7 is a diagrammatic view showing the movement of the second roller to an upper block.

Figure 8 is a diagrammatic view showing the second lower roller moving to its position.

Figure 9 is a diagrammatic view showing

the second upper roller moving to its position.

Figure 10 is a diagrammatic view showing the full group of rollers in the formed sheet.

Figure 11 is a diagrammatic view showing the positions of the rollers reversed, that is to say, the larger rollers at the top and the small rollers at the bottom for making the second sheet of the radiator casing.

Figure 12 is a diagrammatic view which corresponds to Figure 7.

Figure 13 is a diagrammatic view which corresponds to Figure 8.

Figure 14 is a diagrammatic view which corresponds to Figure 9.

Figure 15 is a detail showing one sheet as turned out of this machine.

Figure 16 is a detail showing the second sheet as turned out by this machine.

Figure 17 is a sectional detail of a carriage.

Like numerals of reference indicate corresponding parts in the various figures.

Referring to the drawings, the machine frame is formed of the standards 20 and upper side rails 21 and lower side rails 22.

The upper racks 23 are carried by the side rails 21 and the lower racks 24 are carried by the side rails 22.

The table 25 supports the lower end blocks 26 and 27 extending across the machine and having the recessed faces 28 and 29 respectively.

The upper blocks 30 and 31 extend beyond the blocks 26 and 27 respectively and have the flat faces 32 and 33 respectively.

The upper carriages 34 travel on the racks 23 and are formed with the guide wheels 35 engaging said rails and the guide wheels 36 travelling on the back of said rails.

The driving gears 37 are suitably mounted on the carriages 34 and are driven by power or by hand, as may be desirable, and for the purposes of this invention crank handles 38 are shown, though in all likelihood, these gears will be operatively connected up to a suitable power and engage the racks.

The carriages 34 have the lower extensions 39 with the recesses 40, opposite the flat face 32 of the block 30, and in these recesses 40, the forming rollers 41 are carried. The carriages 42 have the upper guides 43 engaging

the rails and the guides 44, engaging the backs of the rails 24, as well as the operating gears 45 shown as turned by the crank handles 46 and engaging the racks.

5 The rollers 49 are carried in the recesses 48 and are of larger diameter than the rollers 41, as in every case the sheets after being rolled and curled must fit into one another and be spaced apart when used for building a radiator.

10 In the operation of this machine the sheet metal 50 is flanged at one end 51 and inserted between the blocks 26 and 30, the flange 51 engaging the back of the block or engaging a slit in said block as may be found most convenient.

15 The sheet now stretches from the blocks in the direction of the other end of the table and in its first position is lying flat on the table 20 towards its far end.

20 The carriages 42 are now brought forward by means of the rack and gear mechanism, rolling on the plate until they reach the block 26, where the sheet of metal is forced into the recessed face 28. This gives the sheet a very sharp bend at the upper edge of the block, and curls said sheet into the recess as it follows the bed of the said recess 28.

25 The inclination of the sheet is now to rise at the far end and the smaller roller 41 engages the bottom of the sheet, and is moved therealong by the carriages 34, these carriages being driven by this rack and gear mechanism.

30 The result of this operation is that the sheet is curled around the roller 49 and the roller 41 pushes it against the flat face 32, thus the first S shape of the sheet is made.

35 The next operation is the first step repeated only in place of the roller going into the recess it moves up against the first roller put into the recess and thus the second S is started. This is clearly shown in Figures 6, 7, 8 and 9, as the successive rollers are moved to their positions.

40 In Figure 10 the blocks 27 and 31 are brought from the other end and in forcing the block 31 on the recessed block 27, the sheet metal is bent thereunder, so that the result of this bending and curling is a plurality of S shapes in the metal with two straight ends. The sheet is finished by an outside die and curled around to a tubular formation at the end of the radiator sheet.

45 In Figures 11, 12, 13 and 14, the only difference in the operation is that the rollers are reversed. The large rollers are put on top while the small rollers are put on the bottom, this produces a sheet which will fit into and which can be spaced from the first sheet made, and in the formation of each of these sheets the longitudinal spacers 52 are used between the small rollers, and that provides the necessary space within the radiator.

50 In finishing the radiator, this machine is

not concerned, as the ends are offset inwardly and welded, and the other finished pieces placed thereon. The salient feature of this invention is the curling of the sheets so that they will produce this particular form of radiator shown.

What I claim as my invention is:—

1. In a sheet metal radiator forming machine, a frame formed of standards, side rails and a table, racks mounted on said side rails and carriages having a running gear of guiding wheels coacting with said racks and each carriage carrying an operating gear and a crank handle secured to the operating gear, said carriages having roller carrying extensions, upper and lower blocks supported on said table at each end of the machine and forming grips for the ends of a sheet of metal, and rollers of different diameters in upper and lower sets respectively and operated by said carriages towards one set of blocks and travelling alternately and respectively on the top and bottom faces of said sheet and forming a succession of S shapes in the metal.

2. In a sheet metal forming machine, a frame carrying tracks and forming blocks, carriages having roller recesses and travelling on said tracks and upper and lower sets of rollers adapted to enter the recesses of said carriages respectively and to be propelled thereby and to be in turn placed individually under and over said sheet in successive strokes of the carriages in the direction of the forming blocks.

3. In a sheet metal forming machine, a frame carrying tracks and forming blocks, carriages having roller recesses and travelling on said tracks and upper and lower sets of rollers adapted to enter the recesses of said carriages respectively, and to be propelled thereby and to be in turn placed individually under and over said sheet in successive strokes of the carriages in the direction of the forming blocks.

4. In a sheet metal forming machine, a frame carrying tracks and forming blocks having flat and arcuate faces, carriages having roller recesses and travelling on said tracks and upper and lower sets of rollers adapted to enter the recesses of said carriages respectively and to be propelled thereby and to be in turn placed individually under and over said sheet against the flat and arcuate faces of the blocks.

5. In a sheet metal forming machine, a frame carrying tracks and forming blocks, carriages having roller recesses and travelling on said tracks and upper and lower sets of rollers of different diameters adapted to enter the recesses of the carriages respectively and to be propelled thereby and to be in turn placed individually under and over said sheet and forming the sheet in S shapes successively arranged.

6. In a sheet metal forming machine, a

frame carrying tracks and forming upper and lower blocks at each end of the machine, upper and lower carriages having roller recesses and travelling on said tracks and upper and lower rollers of different diameters adapted to enter the recesses of said carriages respectively and adapted to be propelled thereby and to be in turn placed individually under and over said sheet in successive strokes of the carriages in the direction of the forming blocks.

Signed at Montreal, Canada, this 11th day of September, 1928.

LOUIS ARTHUR ROBITAILLE.
